[57] CLAIM

The ornamental design for a roller for removing water
from tennis courts, golf greens and the like, substan-
tially as shown and described.

DESCRIPTION

FIG. 1 is a perspective view of a roller for removing
water from tennis courts, golf greens and the like show-
ing my new design;

FIG. 2 is an end elevational view, taken from the han-
dle end thereof;

FIG. 3 is a side elevational view, the opposite side being
a mirror image thereof; and

FIG. 4 is a top plan view thereof.

The handle portion has been shown fragmentarily in
FIG. 1 for convenience of illustration.
